UNITED STATES PATENT OFFICE.

CARL GABRIELSON, OF SYRACUSE, NEW YORK, ASSIGNOR TO L. C. SMITH & CORONA TYPEWRITERS INC., OF SYRACUSE, NEW YORK, A CORPORATION OF NEW YORK.

CARD PLATEN FOR TYPEWRITERS.

Application filed March 4, 1926. Serial No. 92,306.

This invention relates to improvements in card platen for typewriting machines, and the principal object of the invention is to provide means for holding a card in position with relation to the platen so that the type will strike the card just above its lower edge, or as close to said edge as may be desired.

The invention includes gauges for quickly setting in writing position cards of different lengths and widths. It also provides means for turning the platen with relation to the card holder whereby different portions of the surface of the platen may be used, to prevent it from wearing unduly in any one place.

The invention also comprises a ribbon guard especially designed for use with the card holder, and adapted to act as a guide for the lower edge of a card, and other details contributing to the general purposes of the object of the invention.

The invention is illustrated in the accompanying drawings, in which:

Fig. 1 is a front view of a typewriter platen with the card holder and ribbon guard in operative relation thereto;

Fig. 2 is an end view of the same, looking to the left from the line 2—2 of Fig. 1;

Fig. 3 is a central section on the line 3—3 of Fig. 1;

Fig. 4 is a section on the line 4—4 of Fig. 2;

Fig. 5 is a section on the line 5—5 of Fig. 1;

Fig. 6 is a section on the line 6—6 of Fig. 5;

Fig. 7 shows front and edge views of one 35 of the friction springs for holding the platen yieldingly from turning;

Fig. 8 is a front view of the ribbon guard; and

Fig. 9 is an edge view of the same.

Referring to the drawings, 10 indicates the platen shaft which is removably mounted in the carriage frame 11, as found, for instance, in the well-known L. C. Smith & Bros. typewriter. The platen embodied in the present 45 invention is interchangeable with the ordinary platen of the typewriting machine.

The platen proper 12 instead of being fixed on the shaft, as is customary, is free to revolve on the shaft, but frictionally held in 50 any desired position by means of suitable springs 13, located between the end plates 14 of the platen and head plates 15, 15^a of the card holding frame.

The plates 15, 15^a are connected to hubs 16, 55 16^a which are fixed on the shaft 10, being se-

cured by suitable pins or screws. As shown in Fig. 2, the head plate 15^a is provided with a notch 17, which is engaged by the usual holding pawl 18. The head plates 15, 15^a being rigidly secured on the platen shaft, are 60 thus both prevented from turning and the card holder is thus held in fixed relation to other parts of the machine, with the exception of a slight adjustment in certain parts, which will be presently explained. 65

The head plates 15, 15^a have upward projections 19 between which extend two rods 20 and 21, located above the platen. The rods 20, 21 are preferably rigidly connected together at their middle portions by a brace 70 piece 20^a. Pivoted on the rod 20 are two card supporting arms 22. These arms, as shown, are of light sheet metal having flanges 23 to stiffen them. The rod 21 passes through slots 24 in the lower ends of the flanges 23, 75 which slots permit the arms 22 to rock slightly on the rod 20. Springs 25 coiled about the rod 20 and pressing against the arms 22 and the rod 21, as illustrated in Fig. 5, throw the upper ends of the arms 22 forward normally 80 to hold the lower edge of a card against the platen, as will be explained hereinafter.

The arms 22 of the card holder are provided with slots 26 (Fig. 1) in which are mounted adjustable stops 27 which serve as 85 gauges for the upper edges of the cards. The stops 27 may be adjustably secured in any desired positions on the arms 22. As shown in Fig. 5, they are frictionally held by means of spring washers 28.

Secured to each arm 22 is a finger 29 which is held yieldingly against the platen by the spring 25, before mentioned, and which is adapted to press the lower edge of a card against the platen. The fingers 29, as shown, 95 are rigidly connected to sleeves 30 and the arms 22 are rigidly connected to the same sleeves, the sleeves being pivotally mounted on the rod 20. At their upper ends the fingers 29 are flared outwardly, as at 31, to form throats to receive the lower corners of the cards. The arms 22 and their connected fingers 29 are slidable endwise on the rods 20, 21 and they are held in any position to which they may be adjusted by the friction of the 100 end of the spring 25 upon the rod 21, as will be apparent from inspection of Figs. 5 and 6.

The cooperating ribbon guard 35 is secured to a fixed bracket in the same manner in 110

which the ordinary ribbon guard is secured, and it is provided with the usual gauge 36 to indicate the bottom of the line of print. When it is desired to print on the lower-most margin of a card, the card is made to register with this gauge line 36.

The ribbon guard 35 is provided with two upwardly projecting skeleton fingers 37 which are flared away from the platen at 10 their upper ends 38. These flared ends 38 serve to guide the card in toward the platen and the fingers 37 hold the card close to the platen while printing on the lower margin thereof.

15 The devices described operate in the following manner:

The fingers 29 are L-shaped in cross-section and operate as side guides for the cards. The arms 22 carrying these fingers are adjusted upon the rods 20, 21 so that a card, such as shown at C in broken lines, Fig. 1, will be properly centered with respect to the platen. The gauges 27 are located with respect to the particular size of card to be written upon so that when the upper edge of the card is against the gauge, the lower edge will be in position to receive a line of writing on the lower-most margin of the card, or as close thereto as desired. It will be evident that by sliding the arms 22 toward or away from each other and by moving the gauges 27 up or down, cards of various sizes can be accommodated. When the proper adjustments have been made for a given size of card, succeeding cards may be quickly placed in position for writing and quickly removed. When placing a card in position, the arms are tipped back slightly against the tension of the springs 25 which facilitates sliding the cards down under the fingers 29. This is also facilitated by the outward flare of the upper ends of the fingers, shown at 31. On releasing the arms the fingers 29 press the card to the platen, just above the lower margin of the card, which is to be written upon. The card is thus held close to the platen while its lower margin is fully exposed so that a complete line may be written across the bottom of the card. 45 The outward flare of the upper ends of the fingers 37 of the ribbon guard also facilitates the placing of the card in writing position.

The frame carrying the gauges is fixed with relation to the typewriter carriage by the holding pawl 18 and the platen shaft is likewise fixed. The platen, however, may be rotated upon its shaft to bring new surfaces to the printing point, thus preventing the platen from being worn unduly along a single line. The springs 13 retain the platen in any desired position while permitting the platen to be rotated on its shaft.

As previously stated, the card-writing platen described may be quickly substituted for the usual platen of the machine. The

only other change required is to substitute the special ribbon guard 35 for the usual ribbon guard. It will be understood that the customary spring paper fingers 40 may be used in the ordinary way to assist in holding 70 the lower edges of the cards against the platen.

Having described my invention, what I claim is:

1. In a typewriting machine a card platen 75 comprising a platen shaft, a platen thereon, and a card holding frame comprising head plates mounted on the shaft, means for preventing the plates from turning on the shaft, two rods secured to and connecting said 80 plates, two card supporting arms mounted on and extending upwardly from said rods, said arms being adjustable on the rods for different lengths of cards, gauges adjustable on said arms for adjusting cards of different 85 height to the printing point on the platen, said arms also carrying side gauges for the cards and fingers for pressing the lower margins of the cards to the platen.

2. In a typewriting machine a card platen 90 comprising a platen shaft, a platen thereon, and a card holding frame comprising head plates mounted on the shaft, a rod connecting said plates, and two card supporting arms mounted on and extending upwardly 95 from said rod, said arms being adjustable lengthwise of the rod and carrying gauges for locating the upper edge of a card and a gauge for locating the side edge of a card with respect to the printing point on the 100 platen.

3. In a typewriting machine a card platen comprising a platen shaft, a platen thereon, and a card holding frame comprising head plates mounted on the shaft, a rod connecting 105 said plates, and two card supporting arms mounted on and extending upwardly from said rod, said arms being adjustable lengthwise of the rod and carrying gauges for locating the upper edge of a card and a gauge 110 for locating the side edge of a card with respect to the printing point on the platen, said gauges for locating the upper edge of a card being longitudinally adjustable of said arms for cards of different heights. 115

4. In a typewriting machine a card platen comprising a platen shaft, a platen thereon, and a card holding frame comprising head plates mounted on the shaft, means for preventing the plates from turning on the shaft, 120 a rod adjacent to the platen connecting said plates, two card supporting arms mounted on said rod, fingers connected to said rod and extending into contact with the platen, and spring means for rocking said arms forward 125 to press the fingers toward the platen to hold a card in printing relation to the platen.

5. In a typewriting machine a card platen comprising a platen shaft, a platen thereon, and a card holding frame comprising head 130

plates mounted on the shaft adjacent the ends of the platen, a rod connecting said plates, card supporting arms mounted on the rod, and gauges for locating a card in position for printing, said gauges being carried by the arms, and said platen being rotatable independently of said frame, for the purpose set forth.

6. In a typewriting machine a card platen comprising a platen shaft, a platen thereon, and a card holding frame comprising head plates mounted on the shaft at opposite ends of the platen, a rod connecting said frames, and arms mounted on and extending upwardly from said rod, said platen being rotatable relatively to said card holding frame, for the purpose set forth.

7. In a typewriting machine a card platen comprising a platen shaft, a platen thereon, and a card holding frame comprising head plates mounted on and secured to the shaft, a rod connecting said plates, upwardly extending arms mounted on and adjustable along said rod, and gauges for the upper edge and the side edges of a card mounted on said arms, the platen being rotatable independently of said frame and provided with friction means to hold it in any desired position.

8. In a typewriting machine a card platen comprising a platen shaft, a platen thereon, and a card holding frame mounted on the shaft and extending above the platen, in combination with a ribbon guard having upwardly extending fingers flared away from the platen to facilitate the placing of a card on said frame in position for printing.

9. In a typewriting machine, a platen shaft, a platen on the shaft, a frame having end plates mounted on the shaft at the ends of the platen, means for preventing the frame from rotating about the shaft, card

supporting arms carried by the frame and card gauges carried by the arms.

10. In a typewriting machine, a platen shaft, a platen on the shaft, a frame having end plates mounted on the shaft at the ends of the platen, means for preventing the frame from rotating about the shaft, card supporting arms carried by the frame and card gauges carried by the arms, said platen shaft being removably mounted in the platen carriage.

11. In a typewriting machine, a platen shaft, a platen on the shaft, a frame having end plates mounted on the shaft at the ends of the platen, means for preventing the frame from rotating about the shaft, card supporting arms carried by the frame and card gauges carried by the arms, said platen being rotatable relatively to the platen shaft.

12. In a typewriting machine, a platen shaft, a platen on the shaft, a frame having end plates mounted on the shaft at the ends of the platen, means for preventing the frame from rotating about the shaft, card supporting arms carried by the frame and card gauges carried by the arms, said arms having fingers adapted to press a card against the platen, and spring means adapted to rock the arms to move the fingers toward the platen.

13. In a typewriting machine, a platen shaft, a platen on said shaft arranged to be rotated independently thereof, a frame having end plates mounted on the shaft at the ends of the platen, means for preventing the frame from rotating about the shaft, card supporting arms carried by the frame, and card gauges carried by the arms.

In testimony whereof I hereunto affix my signature.

CARL GABRIELSON.
